BUILDING BLOCK ANCHORING BOLT POSITIONING TOOL

Alfred L. Van Cantie, Brighton, Mich.

Application August 10, 1954, Serial No. 448,903

2 Claims. (Cl. 33—180)

The present invention relates broadly to masons' tools and specifically to a simple and inexpensive tool for positioning anchor bolts in soft mortar in building blocks so that all bolts extending upwardly from the last course of blocks are positioned in alignment and need not be bent to conform to the holes provided for them in the steel or wood beam sills forming the foundations of the structure.

As now constructed, most frame and steel buildings require anchor bolts through the sill beams and each is to be embedded in mortar in one of the holes of a building block of the foundation block course. It is the practice generally to set an anchor bolt in soft mortar and to expect that the eye and hand could position it in the center of the block and exactly vertical. While this is often possible, frequently the mortar sags enough in the hole to misalign the bolt, and the mason, having moved on to other tasks and block courses does not find the misaligned or slanting bolt until the mortar or cement has set, necessitating either replacing the bolt or bending it to as near a vertical position as possible, so that the bolt fits easily in the hole in the sill, plate or beam which follows.

The present invention provides a simple and easily constructed tool which can hold temporarily at least the bolt upright until initial set of the cement or mortar takes place, and also serves to quickly position the bolt at the proper center of the block.

The principal object of the present invention, therefore, is to provide a simple tool for setting anchor bolts vertically in cement building blocks.

Another object of the present invention is to provide a light weight, easily assembled and constructed tool which will stand an average amount of hard usage as given to masons' tools, and is so braced as to not easily get out of plumb, and one which provides an easily read scale and series of notches which indicate common widths of building blocks, so that the mason need only glance at the tool on the block to see that the bolt will be exactly centered therein.

These and other objects and advantages of the present invention will be readily apparent from the following description when considered with the accompanying drawings, in which:

Figure 1 is a view in perspective of a common, cement building block showing the present invention thereon holding an anchor bolt. 60

Figure 2 is a top plan view of the invention.

Figure 3 is a side view in elevation of the invention.

2

Referring in more detail to the drawing, in which like numerals indicate like parts throughout the three views, it will be seen that the invention consists of an upstanding guide member 10 of V-shape, and a horizontally disposed T-shaped support member 11 secured by the mid-point of its cross leg 12 to the lower end 13 of the guide member 10. The portion inwardly from the upper end of the guide member 10 is provided with a scale or rule 14, and the cross leg 12 of the support member 11 is marked or engraved with a rule 15, one edge of which is provided with notches 16 to indicate the common widths 4, 6 and 8 inches of width of the building blocks commonly in use.

A handle 17 with a convenient hole 18 to hang the tool completes the invention, and is secured at one end to the longitudinal leg of the support member 11 and at the other end to the upper end of the guide member 10. The handle serves as a brace to keep the guide member vertically disposed relative to the support member, so that it does not get out of alignment and will hold at least temporarily a bolt, indicated at 19, in soft mortar or cement 20 in the hole 21 in a building block 22, as seen in Figure 1.

While only preferred embodiments have been here shown and described, other embodiments of the present invention may be made within the scope of the appended claims without departing from the spirit of the invention.

What is claimed is:

1. A building block anchor bolt positioning tool comprising an upstanding V-shaped guide member, a horizontally disposed T-shaped support member secured by the mid-point of its cross leg to said guide member at the lower end thereof, said support member being formed on its cross leg with block-width indicating means including a rule and notches in one edge thereof indicating common widths of blocks, said support member being adapted to be supported on the top surface of a building block with said guide member over a hole therein for temporarily centering between its legs an anchor bolt having its lower end embedded in soft mortar in the hole.

2. A building block anchor bolt positioning tool comprising an upstanding V-shaped guide member, a horizontally disposed T-shaped support member secured by the mid-point of its cross leg to said guide member at the lower end thereof, said support member being formed on its cross-leg with block-width indicating means including a rule and notches in one edge thereof indicating common widths of blocks, said support member being adapted to be supported on the top surface of a building block with said guide member over a hole therein for temporarily centering between the legs thereof an anchor bolt having its lower end embedded in mortar in the hole, said guide member being formed at its upper end with measuring indicia, and a handle connecting the longitudinal leg of said support member to said guide member at its upper end for vertically positioning said guide member relative to said support member.
